UNITED STATES PATENT OFFICE.

PATRICK F. MACCALLUM, OF GLASGOW, SCOTLAND, ASSIGNOR OF ONE-FOURTH TO
JAMES REID, OF GLASGOW, SCOTLAND.

NAVIGABLE VESSEL.

Application filed October 25, 1922. Serial No. 596,818.

To all whom it may concern:

Be it known that I, PATRICK FRASER MACCALLUM, a subject of the King of Great Britain, and a resident of Glasgow, Scotland, have invented new and useful Improvements in and Relating to Navigable Vessels, of which the following is a specification.

This invention relates to vessels and machines such as may be termed water mobiles designed for high speed travel.

In Maccallum's prior U. S. Patent specification No. 830,447 is described a vessel having travelling flotation bands which served to support the vessel both when stationary and when travelling.

The construction of such vessels proved too fragile for ordinary conditions.

My present invention consists in a vessel designed for travelling on water at high speed having a central hull capable of sustaining by displacement the total weight of the vessel when at rest, and provided with end drums or wheels, in combination with a flat, or approximately flat, runner belt, or belts, passing over said drums or wheels, and under and over said hull, intermediate anti-friction devices being provided to prevent direct contact of said belt or belts with the hull. The arrangement is such that when the end drums or wheels are driven the runner belt, or belts, will be continuously delivered from the leading drum or wheel on to the water in such manner as to tend to raise the whole vessel on to the surface of the water with a lifting effect proportional to the speed of advance and to the area of the belt, or belts, in contact with the supporting fluid. Furthermore, by causing the belt to travel under and over the hull the frictional resistance incident to the movement of the boat is reduced to a minimum.

My invention further consists in providing the vessel with means designed to assist in raising the vessel to, or near, the surface of the water, and also in providing means to protect the runner belt from the action of broken water or débris.

My invention further consists in features of construction to be hereinafter described and pointed out in the claims.

In order that my invention will be properly understood I have hereunto appended

three explanatory sheets of drawings illustrating various embodiments of my invention and whereon:

Figure 1 illustrates diagrammatically an elevation of an elementary construction of vessel in accordance with my invention, the middle portion thereof having been omitted.

Figure 2 is a section on the line 2—2 Figure 1.

Figure 3 illustrates a view corresponding to Figure 1 of a slightly modified construction, and

Figure 4 is a section on the line 4—4 Figure 3.

Figure 5 illustrates a view corresponding to Figure 1 of a further modification.

Figure 6 illustrates how a vessel as illustrated in the previous figures may be propelled in an emergency.

Figure 7 illustrates a constructional detail.

Figures 8 and 9 illustrate a cross section and part side elevation respectively of the bottom of a vessel and means for guiding and protecting the belt.

Figures 10 and 11 illustrate views corresponding to Figures 8 and 9 respectively of another arrangement of guiding and protecting the belt.

Figures 12 and 13 illustrate a further modification for the same purpose.

Figure 14 illustrates a sectional side elevation and Figure 15 a sectional plan view on the line 15—15 Figure 14 of a further construction of vessel in accordance with my invention.

Figure 16 is a section on the line 16—16 Figure 14, and Figure 17 is a view of the bow of the vessel illustrated in Figures 14 and 15.

Throughout the various figures the same letters are used to designate the same or corresponding parts.

Referring to the drawings.

a designates the hull, *b* the end drums or wheels, and *c* the runner belt. Said belt is about the same width as the bottom of the hull and may be formed of one or more layers of suitable fabric or thin metal, or a combination of those, with transverse stiffeners of timber or light metal section as indicated at *d*. Transverse blades or stops

may be secured to the belt at spaced distances apart, and further, the belt construction is preferably such, that while not intended to support the hull by displacement, its weight in relation to bulk will be such as to prevent accidental loss by sinking in water.

Further for convenience in assembling and dismantling the belt may be made in two or more lengths for bolting or clasping together.

Propulsion is effected by driving the rear drum from an internal combustion engine or other power unit *w* carried by the hull.

15 The elementary vessel described will after starting, progress by stern wheel propulsion, but as speed increases, owing to the lifting action of the runner belt and the attached blades rolling more and more rapidly on to the surface of the water, the vessel as a whole will gradually rise till the hull is practically clear of the water and moving along the inner lower surface of the runner belt, which will, at the same time, have no forward motion in relation to the water supporting it. Skin friction, wave and eddy making resistances and propeller losses are thus practically eliminated, so that great speed may be attained with moderate power expenditure.

As shown in Figures 1 and 2 the drums may be carried in adjustable bearings *g* and *g*¹ secured to extensions *h* and *h*¹ on the hull. Or, as shown in Figures 3 and 4, the drums 35 may be carried by adjustable side plates *i* and *i*¹. In both arrangements the rear drum is capable of a vertical adjustment and the front drum of a horizontal adjustment. To ensure satisfactory performance in 40 rough water a forward wash plate or bow piece *j*, see Figure 5, may be provided. This may be carried on side extensions *j*¹ from the main hull sufficiently in advance of the forward drum to allow passage of the runner belt and its attachment between the drum and the rear of the wash plate or bow piece, the lower rear surface of which may be shaped to over-lap and protect the leading edges of the runner belt. Also to correct 45 tendency to sink aft at high speeds an after body or stern piece *l* of the skimmer type may be supported and positioned by fixed or adjustable side pieces *l*¹ carried by the side of the hull *a*.

50 Tendency to sink aft may alternatively be corrected by the attachment of a couple of skimmer plates or boxes *x*, see Figure 6, to the after sides of the hull. These skimmer attachments may be hinged forward and adjusted aft vertically by screw or other gear *x*¹.

The edges of the runner belt in contact with the water may be protected from side drift currents, floating débris, and tendency 55 to sag by the provision of longitudinal

guard plates attached to the sides, or bottom, of the hull in such a way as to embrace the edges of the runner belt without touching them under usual conditions.

In the construction illustrated in Figures 70 8 and 9 strips *m* of lignum vitæ, or the like, are secured to the bottom of the hull, and on which bear the gun metal or like strips *n* which in turn are secured to the bands *n*¹ of waterproof belting which serve to reinforce the edges of the belt *c*. At spaced distances apart wheels *o* are secured to the hull of the vessel and which are enclosed by cover plates *o*¹, the lower edges thereof being bent inwardly to protect said bands *n*¹.

80 In the arrangement illustrated in Figures 10 and 11 wheels *p* housed in the boxes *p*¹ bear on the reinforcing bands *n*¹, or on anti-friction strips secured thereto. To the underside of the belt *c* guide clips *q* are secured, at spaced distances apart, and which engage with the strips of gun metal or the like *q*¹ of angle section secured to the hull.

85 In the further modification illustrated in Figures 12 and 13 strips of metal *r* of angle section are secured to the bottom of the vessel and with which engage hooks *r*¹ carried by the belt. In such arrangement the wheels shown, in the previously described arrangement are totally eliminated.

90 Figure 7 illustrates an arrangement wherein wheels *u* act on the belt *c*, the anti-friction bearing surface being thereby dispensed with.

95 Two narrow vessels of any of the types hereinbefore described may be connected side by side with accommodation for passengers, cargo, and driving and other machinery arranged between the two hulls, or the vessels may be arranged tandem fashion with a connecting platform between them.

100 A swift passenger craft, or light water mobile with a single hull with fore and aft drums of moderate diameter is indicated in Figures 14 to 18, and whereon the upper portion of the runner belt is supported at any desired height above the floor by rollers or pulleys *t* mounted on a framing *u* supported from the hull; and to afford protection to passengers and propelling and other machinery the spaces below the runner belt may be closed in to any desired extent. Furthermore in the case of small narrow craft as illustrated the hull may be formed 110 with a central well *z* and widened out as at *v* at any convenient height to afford additional interior space for seating or other accommodation.

115 In vessels of the type just described stability is largely secured while in rapid motion by the dynamic action of the rotating members, so that narrow hulls may be safely used.

120 In the event of failure of the runner belt 125

a portion thereof with attached blades may be wound on the rear drum, as indicated by Figure 6, the vessel being then driven after the manner of the well-known stern wheeler.

5 I claim:

1. A vessel comprising in combination a hull capable of supporting the total load when at rest in water, rotatably mounted members located fore and aft of the hull, 10 an endless flat runner belt passing over said members, means for driving the belt at high speed so that the belt travels on the water and supports the hull, and an adjustable wash-plate located in front of the rotatable member at the forward end of the hull said belt being provided with means for minimizing the slip between said belt and said water.
2. A vessel comprising in combination, a hull capable of supporting the total load when at rest in water, rotatably mounted members located fore and aft of the hull, an endless flat runner belt passing over said members, means for driving the belt at high speed so that the belt travels on the water and supports the hull, a stern piece of the skimmer type, and side plates for adjustably mounting said stern piece aft of the rotatable member at the after end of the hull.
3. A vessel comprising in combination, a hull capable of supporting the total load when at rest, or moving slowly in water, rotatably mounted members arranged fore and aft of the hull, an endless flat runner belt passing over said members, guide channels secured to the hull of the vessel and enclosing the edges of the runner belt, reinforcing and anti-friction strips secured inside the runner belt, anti-friction slides of suitable material secured to the hull, and means for driving the belt at a high speed so that the belt travels on the water and supports the hull.
4. A vessel comprising in combination, a hull capable of supporting the total load when at rest, or moving slowly in water, rotatably mounted members arranged fore and aft of the hull, an endless flat runner belt passing over said members guide channels secured to the hull of the vessel and enclosing the edges of the runner belt, reinforcing and anti-friction strips secured inside the runner belt, anti-friction slides of suitable material secured to the hull, intermediate small wheels secured to the hull and arranged to bear on the belt, and means for driving the belt at a high speed so that the belt travels on the water and supports the hull.
5. A vessel comprising in combination a hull capable of supporting the total load when at rest in water, said hull having a narrow bottom and expanded sides to give additional displacement, a frame work erected thereon, adjustably mounted rotatable members located fore and aft of the vessel on said frame work, a flat runner belt provided with antifriction means passing over said rotatably mounted members, and means for driving the belt at a high speed so that the belt travels on the water and supports the hull on the surface of the water.
6. In combination, a vessel adapted to be positioned in a fluid medium, said vessel comprising a hull, rotatably mounted members positioned fore and aft of said hull, an endless belt passing over said rotatably mounted members, one portion of said belt being positioned in said fluid medium, means secured to said hull for enclosing the edges of said belt and for guiding the same, reinforcing antifriction means secured to the inner side of said belt, cooperating antifriction slides secured to said hull, and means for driving said belt at a speed adapted to support said vessel on said fluid medium.
7. In combination, a vessel comprising a hull, members rotatably mounted fore and aft of said hull, an endless belt carried by said members and passing under and over said hull, means secured to said hull for enclosing the edges of said belt, said means being adapted to guide one surface of said belt, and antifriction means for guiding another surface of said belt as it passes underneath said vessel.
8. In combination a vessel, a belt for driving said vessel, and means for reinforcing the edges of said belt, said means being adapted to serve also as antifriction means whereby the power necessary to drive said belt may be reduced to a minimum.
9. A vessel comprising a hull, side plates adjustably secured to the ends of said hull, members rotatably mounted on said plates, and a driving belt carried by said rotatable members, whereby on the operation of the same, said vessel may be propelled in a desired direction.
10. A vessel comprising a hull, side plates adjustably secured to the ends of said hull, members rotatably mounted on said plates, and a driving belt carried by said rotatable members, whereby on the operation of the same, said vessel may be propelled in a desired direction, the side plates and the front end of said vessel terminating in a wash-plate.
11. A vessel comprising a hull, side plates adjustably secured to the front and rear ends thereof, rotatable members secured on said plates, said rotatable members being adjustable vertically and horizontally, respectively, a driving belt carried by said rotatable members and adapted to be actuated by the same, whereby the vessel may be propelled in a desired direction, and antifriction means for guiding said belt.

12. A driving belt having reinforcing strips of gun metal, said reinforcing strips also serving as antifriction means.

inforcing strips of gun metal, said vessel having cooperating strips of lignum vitæ constituting antifriction guiding means.

P. F. MACCALLUM.

13. A vessel comprising a hull having members rotatably mounted fore and aft of the same, and an endless belt carried by said rotatable members, said belt having re-
